CLOTHESLINE PULLEY

William E. Veteran, Niles, Calif., assignor of one-half to Joe N. Viveiros, Niles, Calif.

Application September 26, 1938, Serial No. 231,785

2 Claims. (Cl. 211—119.03)

The well known and common practice of hanging clothes to be dried on a fixed line is highly objectionable for several reasons. For instance it necessitates carrying all of the clothes from the tub to the line and moving the same from time to time as the clothes are hung; it compels the user to travel back and forth many times if the pieces on the line are collected as they dry; it forces the user out into the open in all kinds of weather; it necessitates securing the line to fixed points without intervening obstacles.

With the above and other objectionable features of a fixed line in view, it is one object of the present invention to provide means whereby clothes may be hung upon a line, or removed therefrom, without requiring the user to move from a given spot, enabling the user to place an article on any desired place on the line, and to remove any selected article from the line regardless of its position thereon, without moving from a given spot.

It is also an object of the invention to provide means whereby a line of the character indicated may be readily mounted in a drying yard without interference by any obstacle therein such as a tree, and one that may be mounted upon any desired number of selected supports.

It is another object of the invention to provide means of the character indicated that will permit the full length of the line to be used for the hanging of clothes, as distinguished from that type of pulley line upon which but one-half of the line can be used.

Finally it is an object of the invention to provide means of the character indicated that will be economical to manufacture, simple in form and construction, strong and durable, and highly efficient in its practical application.

In the drawing:

Figure 1 is a side elevation of a device embodying my invention, partly in section and with parts broken away.

Figure 2 is a plan view of a portion of a device embodying my invention, parts being broken away.

The structure when set up in a yard and ready for use comprises a number of identical units, one of which will now be described in detail.

The one unit referred to comprises a bracket 1 which may be mounted upon any suitable support 2 in any suitable manner as by bolts 3.

Disposed upon a vertical axis and mounted on the free end of the bracket 1 is a bolt 4 carrying a bushing 5, a washer 6 being inserted between the bushing and the under side of the

bracket 1 which is channeled as at 7. The washer is square and is kept from rotating by engagement with the channel walls.

At 8 is shown a pulley hub rotatably mounted on the bushing 5 and supported on its head 9. The hub 8 includes a concentric flange 10 upon which is bolted as at 11 an upper circular plate 12 and a lower circular plate 13.

The upper plate 12 has a central portion 14 lying in a plane disposed at right angles to its axis of rotation, and a peripheral portion 15 inclined upwardly and outwardly as shown, forming an angle at 16.

The lower plate 13 is seated flat against the bottom of plate 12 and extends out to the angle 16, where its edge is bent downwardly and curved inwardly as at 17 to form a groove 18 upon which the clothesline is to run.

Upon the bottom of plate 13 are mounted a number of spaced fingers 19, the space between each two fingers being indicated at 20. Each of these fingers 19 extends radially from plate 13 and at an angle thereto to underlie the bottom edge of the flange 17 as at 21, and to form a bottom extension on groove 18.

The clothesline 22 has stops as 23 mounted thereon and spaced apart substantially the same as the fingers 19. Between each two stops 23 and slidably mounted on the line 22 is a link 24 having another link as 25 swingably attached thereto as at 26, the link 26 carrying a clothes clamp 27.

Obviously, a pulley of this kind can be placed on any suitable support in a yard and may vary in number from two upwardly, and arranged to encompass any obstructions that must be avoided. Since the pulley itself rotates in a horizontal plane, or substantially so, as many as desired may be distributed about a yard in the same horizontal plane, with a single line extending around all of them. The line cannot drop off of the pulley due to the arrangement of the fingers 19, yet the line 22 and the several hangers 24 can move freely on the pulley because the fingers are so spaced as to permit the hangers 24 to pass therebetween, the stops 23 maintaining the hangers 24 in position for such engagement.

It is to be noted that the side edges of each finger 19 converge to form a rounded tip on its free end, and that the opposing edges of adjacent fingers therefore converge inwardly and are widely spaced to freely receive the hangers 24. Since each hanger 24 can slide on the line between two stops 23 it readily takes its proper place between 25

two fingers on the pulley because it can slide down any edge it contacts.

5 While the pulley is shown as being mounted upon a vertical axis the axis may be inclined somewhat so the plane in which the pulley rotates will be inclined downwardly and away from the supporting bracket 1 to assist in maintaining the line in its seat in the pulley groove.

It is to be understood, of course, that while 10 I have herein shown and described but one specific embodiment of the invention, changes in form, construction, and method of assembly and operation may be made within the scope of the appended claims.

15 I claim:

1. In combination, supporting means, a grooved pulley suspended therefrom to rotate about a vertical axis, said pulley having one side of its groove formed into radially extending and spaced fingers laterally inclined relative to the plane of the 20

pulley, a line operable in said groove, said line having hangers slidably mounted thereon, and hanger stops disposed on the line and spaced thereon in accordance with the spacing of the fingers on the pulley.

2. In combination, supporting means, a grooved pulley suspended therefrom to rotate about a vertical axis, said pulley having one side of its groove formed into radially extending and spaced 10 fingers laterally inclined relative to the plane of the pulley, a line operable in said groove, said line having links slidably mounted thereon to depend therefrom, each link having another link 15 swingably attached thereto, the second link having a clothes clamp mounted thereon, and hanger stops mounted on the line and spaced thereon in accordance with the spacing of the fingers on the pulley.

WILLIAM E. VETERAN. 20
